UNITED STATES PATENT OFFICE.

FREDERICK KYLE, OF MILTON, OREGON.

TLTING BIN.

1,112,296.

Specification of Letters Patent. Patented Sept. 29, 1914.

Application filed August 5, 1913. Serial No. 783,144.

To all whom it may concern:

Be it known that I, FREDERICK KYLE, a citizen of the United States, residing at Milton, in the county of Umatilla and State 5 of Oregon, have invented new and useful Improvements in Tilting Bins, of which the following is a specification.

This invention relates to tilting bins for household and other uses, and its object is 10 to provide a tilting bin or container of simple and improved construction which may be easily manipulated and which may very conveniently be detached or removed from its casing when necessary for the purpose of cleaning the same.

A further object of the invention is to simplify and improve the construction and arrangement of the pivot on which the bin is supported as well as the stop means whereby 20 the movement of the bin is limited when tilted or swung from a closed to an open position.

With these and other ends in view which will readily appear as the nature of the invention is better understood, the same consists in the improved construction and novel arrangement and combination of parts which will be hereinafter fully described and particularly pointed out in the claim.

30 In the accompanying drawing has been illustrated a simple and preferred form of the invention, it being, however, understood that no limitation is necessarily made to the precise structural details therein exhibited, 35 but that changes, alterations and modifications within the scope of the claim may be resorted to when desired.

In the drawing,—Figure 1 is a side elevation, partly in section, showing the bin 40 closed. Fig. 2 is a similar view showing the bin open. Fig. 3 is a transverse sectional view taken on the line 3—3 in Fig. 1.

Corresponding parts in the several figures are denoted by like characters of reference.

45 The improved bin B is mounted in a casing C which may be made of a suitable size to contain a single bin, or it may constitute a portion of a kitchen cabinet or other structure or of a store counter, or the like. The 50 bottom of the casing supports a cross bar 10 having terminal pintles 11. The bin B comprises side members 12, rear and front members 13, 14 and bottom members 15, 16, the latter being disposed in front of the member 55 15 and inclined from thence upwardly to the front member 14. The side members 12 are

extended below the rearward bottom member 15 to form brackets 17, each having a recess or notch 18 to engage one of the pintles 11 of the cross bar 10 upon which the bin or container will thus be tiltably supported. The notches 18 are of a depth exceeding the diameter of the pintles 11 which are spaced above the bottom member 20 of the casing, so that while the bin may be 60 readily elevated from or restored to its initial position in the casing, the notches will at all times safely engage the pintles and prevent accidental disengagement. The casing C, the front of which is open for the reception of the bin is provided at the lower end thereof with a cross piece 19 which extends upwardly from the front edge of the bottom member 20. The side members 12 of the bin are each cut away at their lower forward 65 portions to produce a recess 21 having an edge 22 which is concentric with the pivotal axis of the bin when the latter is mounted in position and another edge 23 which is radial thereto. The recesses 21 accommodate the cross piece 19 of the casing, said cross piece constituting a stop that lies in the path of the radial edges of the recesses 21 while, owing to the curvature of the edges 22 of said recesses, the bin may be freely 70 75 80 85 tilted about its pivotal axis to an open or a closed position. When the bin is closed the front member 14 thereof abuts on the front of the casing; when the bin is open the lower edge of the front member 14 engages the outer face of the cross piece 19, while the radial edges 23 of the recesses 21 abut on the upper edge of said cross piece 19, thereby retaining the bin in an open position.

To remove the bin from the casing, it is 90 first tilted to its open position and is then lifted to disengage the recesses or notches 18 from the pintles 11, after which the bin may be easily lifted out.

It will be seen from the foregoing that I 100 have produced a very simple and efficient tilttable bin or container which may be effectively used in stores or households for the purpose of storing flour, sugar and other merchandise. When constructed for family 105 use the casing may be equipped with a bread board 24 which is slidably fitted beneath the top of the casing, as shown.

Having thus described the invention, what is claimed as new, is:

110 In a device of the class described, a casing open in front and having at the lower end of

the front opening a transversely disposed cross piece, a cross bar secured within the casing on the bottom member thereof in rear of and parallel to the cross piece, said cross bar being provided at the ends thereof with pintles spaced from the bottom of the casing, and a bin having front and rear members, angularly disposed bottom members and side members extending below the front, rear and bottom members, said side members being provided with notches engaging the terminal pintles of the cross bar and of a

depth exceeding the diameter of said pintles, and said side members being also provided adjacent to the front member with recesses 15 having arcuate edges concentric with the pivotal axis of the bin and straight edges radial thereto.

In testimony whereof I affix my signature in presence of two witnesses.

FREDERICK KYLE.
